METHOD OF REINFORCING GARMENTS

Hyman Koppel, Revere, Mass.

Application March 24, 1948, Serial No. 16,737

1 Claim. (Cl. 2—243)

1

This invention pertains to garment manufacture, and more especially to a novel method of applying a reinforcing tape or the like to a garment part, for instance, between the plies of a coat lapel.

Customarily, in making a coat, the rear ply of the lapel is integral with the breast portion of the coat material. The breast portion of the coat, including this rear ply of the lapel, is usually lined with a stiffening material, for instance, canvas or hair cloth, and a piece of strong reinforcing tape is arranged along the edge of the lapel portion overlying the stiffening material and is sewed along each of its edges to the garment material. The front ply of the lapel is usually integral with the front facing of the coat and is of the same material as the garment proper. This front ply is stitched to the rear ply of the lapel along its outer edge by through-and-through stitches which are usually the same stitches which unite one edge of the tape to the rear ply of the lapel. After the opposite edge of the tape has been stitched in place, the parts are turned so as to dispose the through-and-through seam and the lining and tape at the inside of the lapel. The through-and-through stitches are usually made by a straight needle, whether the operation be carried out by hand or by a sewing machine. The stitches which anchor the opposite edge of the tape in place are blind stitches, for if they were to pass completely through the garment fabric they would show in the finished garment on the front face of the lapel. These blind stitches may be made by hand or by a blind stitch machine, but according to prior practice the through-and-through seam along one edge of the tape is first made, and then the seam which unites the other edge of the tape to the garment material is made as a separate and independent operation.

The through-and-through stitches are usually quite fine, for example, from 12 to 14 to the inch, whereas the blind stitches are coarse stitches, for example, 4 to the inch. Since the tape is first attached along one of its edges by the fine through-and-through stitches, and since the latter are made with the thread under substantial tension, there is a tendency to cause the tape to curl or twist as a result of this first operation, and in making the blind stitch seam, the tape must be straightened so as to lie smooth and flat, otherwise the lapel will not have the desired finely finished appearance.

The present invention has for its object the avoidance of the above difficulty and the performance of the reinforcing operation more ex-

pediently than formerly. Thus, according to the present invention, the opposite edges of the reinforce tape are sewed to the garment material simultaneously, one edge being secured by through-and-through stitches passing completely through the garment material, and the other edge being attached by blind stitches passing through the tape, but only part way through the combined thickness of the stiffening and garment material. Since the through-and-through stitches are finer (more to the inch) than the blind stitches, the invention contemplates the formation of a single blind stitch while a plurality of the through-and-through stitches are being formed. Thus, for example, if the operation be carried out by machine, the mechanism for actuating the two needles must be so geared as to provide the desired relative speed of stitch formation in making the two seams. If the operation be carried out by hand, the operator will first form several (for example, 3 or 4) of the through-and-through stitches, and then, with a separate needle, will form a single one of the blind stitches, etc. In following this procedure both edges of the tape are progressively anchored to the garment material as the operation proceeds, and thus there is no chance for the tape to be unduly contracted along one edge so as to curl or twist before its opposite edge is properly anchored.

While, as above suggested, the simultaneous seam formation can be performed by hand by the use of two separate needles, it is contemplated that it may be carried out by machine, and that for that purpose a single machine, provided with a straight needle and a curved needle (with the usual concomitant sewing machine elements, for example, presser foot, tape feed, bobbin or looper, tensions, etc.) will be employed in performing the operation.

In the accompanying drawings, wherein the mode of procedure is diagrammatically illustrated by way of example:

Fig. 1 is a fragmentary plan view showing the inside of the breast portion of a garment, indicating the rear ply of the lapel with the stiffening canvas and reinforcing tape applied thereto, in accordance with the present invention;

Fig. 2 is a fragmentary transverse section on the line 2—2 of Fig. 1, to enlarged scale;

Fig. 2^a is a view similar to Fig. 2 but showing a slightly different arrangement of stitches;

Fig. 2^b is a similar view, illustrating the application of a reinforce tape to a single thickness of material;

Fig. 3 is a fragmentary front view of the corner of the completed lapel;

Fig. 4 is a fragmentary section, to very large scale, on the line 4—4 of Fig. 3;

Fig. 5 is a fragmentary plan view, showing a piece of fabric having a reinforcing tape secured at its opposite edges to the fabric by a through-and-through stitched seam and a blind stitched seam, respectively, the seams being shown to large scale to illustrate a desirable form of blind stitching; and

Fig. 6 is a diagrammatic, fragmentary, perspective view, partly in vertical section and to large scale, showing portions of a sewing machine designed for simultaneously stitching both edges of the tape.

Referring to the drawings, the numeral 1 designates the material forming a portion of the breast of a coat, a portion of the armscye being indicated at 2. The lapel portion is indicated generally at 3, this lapel portion having the upper edge 4, the corner 5, and the downwardly extending edge 6.

In Fig. 1 the inner surface of the material 1 is shown, and, in the making of a coat or similar garment, it is usual to apply stiffening material 7, for example, a ply of canvas or hair cloth, to the inner surface of the garment material which is to form the lapel, this front ply of the lapel usually being integral with the material forming the breast portion of the garment. This reinforcing canvas 7 is secured to the garment material, with its edge close to the edge of the garment material, by blind stitches (some of which are indicated at B) which only pass part of the way through the garment material so that they do not show at the front of the garment.

In order to prevent the edge of the garment material at the lapel from stretching during use, it is customary to provide a reinforcing tape 8 which extends along the edge 4 of the lapel around the corner 5 and then downwardly along the edge 6 nearly to the bottom of the lapel. The opposite edges of this tape 8 are stitched to the garment material by seams 9 and 10, respectively. The tape 8 is usually of woven, narrow-ware textile fabric having selavage edges, and is firm and strong and resistant to longitudinal stress. The tape is drawn from a supply and progressively delivered so as to extend along the edge of the garment material as the sewing operation proceeds. The stitches which form the seam 9 are through-and-through stitches passing completely through the tape and canvas 7 and also through the full thickness of the garment material 1 (Fig. 2). On the other hand, the stitches of the seam 10, which secure the inner edge of the tape, are blind stitches which do not pass completely through the garment material 1. These stitches may pass only through the canvas 7 (Fig. 2) or through the canvas and through a portion of the thickness of the garment material 1 (Fig. 2a). Usually in making the garment, the material which is to form the rear ply 11 of the lapel and which is usually like the material forming the breast portion of the garment, is united to the material 1 along the edge of the lapel by the same seam 9 which attaches the tape 8. In stitching the parts together they are arranged, as illustrated in Fig. 2, with the garment material 1 superposed on the rear ply 11; with the canvas 7 resting on the material 1 and the tape disposed on the canvas.

The operation of securing the tape and the other parts together may be carried out by hand, although it would ordinarily be carried out by the

use of a sewing machine. In the past the seams 9 and 10 have been formed successively, requiring two separate and independent operations, and when a machine was used, the employment of two different machines.

The stitches forming the seam 9 are usually quite fine, that is to say, from 12 to 14 per linear inch, and the stitches are formed with the thread under substantial tension in order to make a firm seam and to secure the parts closely together. The formation of such a seam comprising closely spaced stitches drawn under substantial tension tends to shorten the edge of the tape 8 so that the opposite edge of the tape tends to curl, and in forming the seam 10 the tape must be laid down smoothly and pulled taut transversely in order that it may be flat and thus avoid the formation of a lumpy lapel. Usually the stitches forming the seam 10 are much coarser than those forming the seam 9, for example, a blind stitch seam may have only 3 or 4 stitches per inch.

In accordance with the present invention, and in order to avoid the twisting and distortion of the tape above referred to, it is proposed to form the seams 9 and 10 simultaneously. Thus, if the operation be carried out by hand, the operator, using the customary straight needle, will make 3 or 4 of the stitches of the seam 9 and then, using another needle and thread, will make a stitch of the seam 10. He will then make 3 or 4 more stitches of the seam 9 and another stitch of the seam 10, etc., progressing from one end of the tape to the other. In this way the tape is anchored simultaneously at its opposite edges to the garment material so that the tape is not initially distorted, and in the finished garment has no tendency to pull the lapel out of proper shape.

If the operation is to be carried out by a sewing machine, apparatus such as generally suggested in Fig. 6 may be employed. Such apparatus, in the nature of a duplex sewing machine, would comprise the usual thread tension and work feed (not shown) and the usual needle bar 12 carrying the straight needle 13 cooperating with customary parts, such as a looper or bobbin (not shown) to form the through-and-through stitches of the seam 9. Preferably a trimming knife 14 would be secured to the needle bar so as to trim off surplus material T (Fig. 6) from the edge of the lapel as the operation proceeds.

A curved needle 15 mounted upon a yoke 16 oscillated by appropriate mechanism, for example, as illustrated in the patent to Lewis, No. 1,172,812, dated February 22, 1916, and cooperating with other usual elements of a blind stitch sewing machine, including a looper or bobbin, not shown (dependent upon whether a chain or lock stitch is to be formed) may be employed in forming the seam 10. An appropriate blind stitch seam is illustrated at 10 in Fig. 5, this being a chain stitch type of seam using a single thread. Preferably such a machine would be provided with means for progressively feeding the tape 8 in proper relation to the needles, such tape-feeding devices being well known in the sewing machine art, and the machine would likewise be provided with a presser foot (not shown) for holding the work in position as the stitches are formed, and with appropriate feed mechanism for advancing the work. Since the blind stitches forming the seam 10 are less in number per inch than the stitches of the seam 9, suitable reduction gearing connections would be provided so that the

needle 15 would be actuated once for several oscillations of the needle 13. Preferably, in such a machine operation, the blind stitch needle 15 would penetrate the work at the same time that the needle 13 is penetrating the work, but this is not essential to the proper formation of the seams.

After the seams 9 and 10 have been formed, the material forming the lapel is turned, as shown at Fig. 4, thus disposing the lining or reinforcing canvas 1 as well as the seams 9 and 10 within the thickness of the lapel so that they are invisible, it being noted that the stitches of the seam 10 do not pass through the material 1 of the garment so that there is no seam visible at the front of the lapel, the finished lapel appearing at the front, as shown in Fig. 3.

While, as above suggested, there will usually be 3 or 4 of the through-and-through stitches of the seam 9 for each blind stitch of the seam 10, the relative number of stitches forming the two seams is of no substantial consequence so far as the present invention is concerned, the invention being directed to the simultaneous formation of these seams so as thereby to avoid twisting or curling of the reinforce tape and incidentally speeding up production if the operation be carried out by means of a duplex sewing machine such as above suggested.

As above specifically suggested, the present method is very useful in making garment lapels, 30 but it may be applied in any instance when a reinforce tape is to be applied, using blind stitches at one edge, as illustrated in Fig. 2^b, where the tape 8 is shown thus secured to a single thickness 20 of material.

I claim:

That method of reinforcing a garment part by the application thereto of a reinforcing tape which comprises as steps assembling the tape and

garment part by laying the tape progressively along one edge of the garment part and, while so progressively laying the tape, uniting one edge of the tape to the garment part by through-and-through stitches all of substantially the same predetermined length and made by a straight sewing needle while concomitantly uniting the opposite edge of the tape to the garment part by blind stitches made by the use of a curved needle, the latter stitches all being of substantially the same length but exceeding the through-and-through stitches in length so as to provide more stitches per linear inch in one seam than in the other, said blind stitches passing through the tape but failing to pass completely through the material of the garment part, the opposite edges of the tape being progressively anchored to the garment as the sewing operation proceeds in order that there is no chance for the tape to be unduly contracted along one edge so as to curl or twist before its opposite edge is properly anchored.
